UNITED STATES PATENT OFFICE.

GEORGE AUER, OF WHITE PLAINS, NEW YORK.

CONCRETE FENCE CONSTRUCTION.

1,280,632.

Specification of Letters Patent.

Patented Oct. 8, 1918.

Application filed September 4, 1915. Serial No. 48,999.

To all whom it may concern:

Be it known that I, GEORGE AUER, a citizen of the United States, residing at White Plains, in the county of Westchester and the 5 State of New York, have invented certain new and useful Improvements in Concrete Fence Construction, of which the following is a specification.

My invention relates to the construction 10 of reinforced concrete fences, serviceable especially as guard rails along country highways and in other places. The object is to enable the production of a strong, durable fence from separately formed sections, 15 which are assembled in a novel manner, as will hereinafter be more particularly set forth. The fence, while made of previously formed units, possesses the strength and solidity of a monolithic structure and be- 20 cause of its construction is less expensive and easier to make and erect. In addition, it may be taken down without substantial injury to the parts, which may be set up again elsewhere.

25 In the accompanying drawings:

Figure 1 is a side elevation of a portion of a fence embodying my invention; Fig. 2 is a fragmentary sectional elevation showing the meeting ends of two top rail sections tied 30 to the top of one of the posts preparatory to the completion of the joint; Fig. 3 is a similar view showing the joint completed; Fig. 4 is a vertical cross-section taken on the line 4—4 of Fig. 3, taken at the meeting 35 ends of two rails. Fig. 5 is a plan view of Fig. 2; and Fig. 6 is a horizontal section on the line 6—6 of Fig. 4.

The posts 1 are cast separately in suitable molds, either on the job or elsewhere. In 40 the sides of the posts as molded are sockets 2, and reinforcing rods 3 and 4 are embedded in the posts and extend throughout the length thereof. The number and arrangement of these reinforcements may be 45 varied, but, as shown, there are five, one adjacent each corner and one in the middle.

In accordance with the invention, one or 50 more embedded members project from the top of each post for engagement with em- bedded members in the top rail sections. In the particular instance shown, there is one 55 projecting member for each post, the same being the middle reinforcement 4, which is extended above the post while the others ter- minate at or below the upper end thereof;

but manifestly the precise details may be varied.

The top rail consists of separately formed sections 5, which extend approximately from center to center of the posts, their ends 60 being supported substantially in abutting relation on the tops thereof. The said sections, like the posts, are cast in appropriate molds, wherein they are given the ornamental formation shown, or such other shape as may 65 be desired. These sections have members embedded therein to engage the projecting post members 4, in order to tie the rail sections to each other and to the posts; and the engaging portions of the said members, after 70 the parts are in place, are covered by bodies of concrete which is poured in liquid or plastic condition into recesses in the meeting ends of the rail sections, thereby both protecting the metal members and forming a key or in- 75 tegral union between the parts.

The top rail sections have three or other suitable number of longitudinal reinforcing rods 6 embedded therein at the time the sections are made, the same extending through- 80 out the length of the sections and one or more of them in each section having projecting eyes 7 at their opposite ends. Preferably it is the central rod which is so constructed. The said rods may be slightly off- 85 set at their ends near the eyes, so that the latter are brought into superimposed relation when the sections are assembled end to end, as will be clear from Fig. 2. The pro- jecting ends of the rods 4 are received with- 90 in and extend above these eyes, and are threaded as indicated at 8 in order that nuts 9 may be screwed down upon the eyes, to hold the rail sections against all possibility 95 of upward movement.

The rail sections as molded are formed with recesses 10 in their ends, which when the sections are assembled form pockets ex- tending downward from the top of the rail to the posts, the said pockets being of suf- 100 ficient size to accommodate the eyes, the nuts, and a wrench for applying the lat- ter. After the parts are in position and the nuts 9 or equivalent retaining devices have been applied, the pockets are filled with 105 fluid concrete or cement, which hardens and forms the keys 11. Each pocket is prefer- ably, though not in all cases necessarily formed half in one of two meeting rail ends and half in the opposed rail end, this con- 110

struction having the advantage of affording an integral bond which extends into both rail sections. It will be apparent that all the metal parts of the fence are embedded; 5 so that their deterioration due to rust as also discoloration of the concrete from the same cause are rendered impossible. All separation of the post and rail members is effectively prevented by the fastening devices, 10 supplemented by the integral bodies 11.

The fence is completed by intermediate rail sections 14, separately molded like the others and containing suitable reinforcing 15 elements. These rail sections are inserted at their ends into the sockets 2 in the posts.

My fence in contradistinction to most if not all prior concrete fences of an integral character may be readily taken down and 20 put up again. All that is necessary is to break out the cast-in keys of concrete and disengage the tying means from the projecting post members. The fence is set up again in the manner already described and plastic 25 material again filled into the pockets at the adjoining ends of the top rail sections.

The present application is for matter divided out of my prior application for concrete fence construction, filed October 2d, 30 1914, Serial Number 864550, upon which Patent Number 1,149,613 of Aug. 10, 1915 has been issued. In the embodiment of the invention claimed herein the elements 7 of the tying means are formed on the opposite 35 ends of reinforcements which are embedded in the top rail sections as formed, extending throughout the length thereof. This construction is covered generically in my patent aforesaid, but the specific claims of that 40 patent are directed to a different species, namely one in which the embedded members projecting from the top of the posts are engaged by metal plates or their equivalents placed in pockets in the adjoining rail ends 45 and embedded wholly within the keys of

concrete cast therein. While the present application bears a specific relation to the prior case, it will be understood, of course, that I do not limit myself herein to the precise construction illustrated.

50

What I claim is:

1. A reinforced concrete fence, comprising reinforced concrete posts, said posts having members embedded therein as formed and projecting at the tops thereof, separately formed reinforced concrete top rail sections, the adjoining ends of which rest on top of the posts, said sections being provided as formed with recesses at their ends forming pockets extending from the top down to the posts and receiving the projecting ends of the embedded post members, tying members embedded in the rail sections and having their ends projecting into said pockets and there engaged with the post members, and bodies of concrete cast into said pockets and embedding the engaging portions of the post and rail members.

55

2. A reinforced concrete fence, comprising reinforced concrete posts, said posts having members embedded therein as formed and projecting at the tops thereof, separately formed reinforced concrete top rail sections, the adjoining ends of which rest on top of the posts said sections being provided as formed with recesses at their ends forming pockets extending from the top down to the posts and receiving the projecting ends of the embedded post members, 70 tying members embedded in the rail sections and having their ends projecting into said pockets and there engaged with the post members, retaining devices within the pockets upon said projecting post members 75 above the tying members, and bodies of concrete cast into said pockets and embedding the engaging portions of the post and rail members and the said retaining devices.
